UNITED STATES PATENT OFFICE

NORMAN E. McCORMICK, FRANK J. DEARINGER, AND EDMOND D. STEWART, OF KANSAS CITY, MISSOURI; SAID DEARINGER AND SAID STEWART ASSIGNEES TO SAID McCORMICK

MAGAZINE GUN

Application filed June 14, 1930. Serial No. 461,094.

Our invention relates to improvements in magazine guns. It relates particularly to an auxiliary magazine adapted for releasable attachment to the gun stock of a magazine gun of usual type, whereby a largely increased number of shells may be supplied to the gun over what is usually stored in the usual magazine thereof.

5

One of the objects of our invention is to provide a magazine gun of usual type provided with novel means by which it may be used with the usual magazine equipment, or with a novel auxiliary magazine which is simple in construction, cheap, durable, not 10 likely to get out of order, which may be easily attached to or detached from the gun stock, which is easily and quickly operated, and which is reliable in its operation.

The novel features of our invention are 15 hereinafter fully described and claimed.

In the accompanying drawings, which illustrate the preferred embodiment of our invention,

Fig. 1 is a reduced side elevation of a gun 20 provided with our improvement.

Fig. 2 is an enlarged side view, partly broken away, of our improved auxiliary magazine shown attached to a gun stock which has been adapted thereto, and which is shown 25 in longitudinal section.

Fig. 3 is a side view of the member having the spiral conduit and shown attached to a gun stock, which is in section and partly broken away.

Fig. 4 is an enlarged sectional view of the 30 rear end of the nozzle.

Fig. 5 is an enlarged inside view of the revolute member and the spring attached thereto.

Fig. 6 is an enlarged section on the line 35 6—6 of Fig. 2.

Fig. 7 is a section on the line 7—7 of Fig. 2.

Fig. 8 is a longitudinal section of the gun 40 stock shown provided with the ordinary shell feed, the auxiliary magazine being removed.

Fig. 9 is an enlarged top view of a portion 45 of the usual shell feeding device, and a part of the locking tube which holds it in the auxiliary receptacle in the gun stock.

Fig. 10 is an enlarged section on the line 10—10 of Fig. 6.

Similar reference characters designate similar parts in the different views.

1 designates the usual gun stock having 55 therein the usual magazine tube 2 adapted to receive therein the usual tubular container 3 in which is mounted the usual coil spring 4, which is adapted to feed shells 5 forwardly in the tube 2 into the gun breech 6.

The stock 1 has an arcuate notch 7 cut in its under side, which notch communicates with a lateral opening in the under side of the tube 2, which opening, designated by 8, is closed by the container 3, when the latter is inserted 60 in the tube 2, as shown in Fig. 8.

The notch 7 is adapted to have removably fitted therein a support comprising a circular member 9, when the container 3 is removed from the tube 2, which member 9 is 65 a part of our improved auxiliary magazine.

The periphery of the support 9 has attached to it a plate 10 having a lateral notch 11 adapted to receive a securing pin 12 mounted in the under side of the stock 1.

The support 9 on its inner side is provided with an involute spiral groove in which is fitted a spiral metal strip 13, which forms a shell receiving conduit, the outer end of which terminates in a curved tube 14 which 75 forms a discharge nozzle, the outer end of which is adapted for insertion into the opening 8 of the tube 2, Figs. 2 and 3.

Shells 5 are inserted in the conduit in the channel 15 formed between the coils of the 80 strip 13. To feed the shells forwardly through the channel 15 and nozzle 14 into the tube 2, and thence into the breech 6, the following described mechanism is provided.

A circular revolute cover member 16 having 85 extending therethrough an axial pin 17 covers the channel 15 and a part of the nozzle 14. The pin 17 is mounted in a central bearing tube 18 in the support 9, said pin having

an annular shoulder 19 which bears against 90 the tube 18. One end of the pin 17 is threaded and has fitted on it a nut 20 which bears against the outer end of the tube 18, thus 95 releasably anchoring the pin 17 in the support 9.

The member 16 is revoluble on the pin 17 and has mounted concentric with the pin 17 on the inner side of the member 16 an annular spring barrel 21, Figs. 5 and 7. Within the barrel 21 is a spiral spring 22 the inner end of which is fastened to the pin 17 and the outer end of which has a loop 23 adapted to receive a pin 24 mounted in the inner side of the support 9.

10 A follower for traveling in the channel 15 is provided consisting in a plate 25 having one end pivoted to a pin 26 mounted in the outer side of the revoluble member 16. The other end of the plate 25 is provided with a 15 transverse hole in which is slidably mounted a pin 27, which is adapted to extend into the channel 15, and which is adapted for lateral travel in a slot 28, which extends in a curve inwardly from the periphery of the member 20 16.

For normally forcing the pin 27 inwardly, it is encircled by a coil spring 29, Fig. 6, one end of which bears against the inner side of the plate 25, and the other end of which 25 bears against a pin 30 in the pin 27.

The inner end of the pin 27 has mounted on it a friction roller 31 which is adapted to bear against the rear end of the rear shell 5 in the channel 15. By pulling outwardly the 30 pin 27, it and the roller 31 are withdrawn out of the channel 15 to enable the follower plate 25 being swung laterally, so as to bring the pin 27 from the outer coil of the conduit channel 15 to the inner coil thereof.

35 The revoluble cover member 16, in addition to its function of covering one side of the conduit channel 15, serves as a support for the spring barrel 21 and the follower roller 31 and its supporting means, and as a means 40 for winding the spiral spring 22 which revolves the cover member and the parts carried thereby.

As the cover member 16 is removable, the 45 spiral channel 15 can be filled with shells without having to detach the magazine from the gun.

When the auxiliary magazine is to be used, the container tube 3 and its coil spring 4 are withdrawn from the tube 2, and inserted in 50 a receptacle comprising a hole 32 extending inwardly from the end of the stock 1, Figs. 2 and 8. In the outer portion of the hole 32 is a tube 33 through which extends the tube 3, the latter has an outwardly extending pin 55 34 which, when the tube 3 is turned, enters a notch 35 in the tube 33, Figs. 2 and 9. The tube 2 is also provided with a notch 36 for receiving the pin 34.

To releasably hold the pin 27 retracted, it 60 has through it a pin 37 adapted to rest on the outer end of a boss 38 on the plate 25, said boss having a slot 39 adapted to receive the pin 37, when the pin 27 is turned, thereby permitting the spring 29 to force the pin 27 65 into the conduit channel 15.

In the operation of the gun with the auxiliary magazine, the support 9 is attached, as described to the stock 1, the container tube 3 having been withdrawn, and the curved nozzle 14 inserted into the opening 8. The 70 follower plate 25 is swung in the slot 28 to a position in which the pin 27 can enter the channel 15 at the inner end thereof.

The channel 15 is then filled with shells 5, the rear one being against the roller 31 of the 75 follower pin 27. The revoluble member 16 is then mounted on the channel strip, or rather over the same, and the pin 17 is inserted through the bearing tube 18 and the nut 20 is mounted on the pin 17. The loop 23 is also fitted over the pin 24, after which the 80 member 16 is revolved clockwise, as viewed in Fig. 2, thus winding the spring 22. The pin 27 is in the channel 15 so that, when the member 16 is released, the spring 22 will 85 revolve the member 16 counter clockwise, as viewed in Fig. 2, thus feeding the shells 5 out through the nozzle 14 into the tube 2, as fast as the gun is fired.

The follower pin 27 will travel in the channel 15 to the nozzle 14.

When it is desired to use the gun without the auxiliary magazine, the latter is detached from the stock 1, and the spring container tube 3 and its spring 4 are reinserted into the 95 tube 2.

We do not limit our invention to the structure shown and described, as many modifications, within the scope of the appended claims, may be made without departing from 100 the spirit of our invention.

What we claim is:—

1. In a magazine gun, the combination with a gun stock having a shell receiving tube discharging into the gun breech, of a support on said stock having a shell receiving conduit discharging into said tube, a cover member revoluble on said support and covering one side of said conduit, a follower extending into and adapted for travel in said conduit against the rear shell therein and engaged by said member and adapted, when said member is revolved in one direction, to forwardly feed the shells, and means for normally revolving said member in said direction.

2. In a magazine gun, the combination with a gun stock having a shell receiving tube discharging into the gun breech, of a support on said stock having a spiral shell receiving conduit discharging into said tube, a cover member revoluble on said support and covering one side of said conduit, a follower extending into and adapted for travel in said conduit against the rear shell therein and engaged by said member and adapted, when said member is revolved in one direction, to forwardly feed the shells, and means for normally revolving said member in said direction.

3. In a magazine gun, the combination with a gun stock having a shell receiving tube discharging into the gun breech, of a support on said stock having a shell receiving conduit discharging into said tube, a cover member revolute on said support and covering one side of said conduit, a follower extending into and adapted for travel in said conduit against the rear shell therein and engaged by said member and adapted, when said member is revolved in one direction, to forwardly feed the shells, and a spring connecting said support and said member and adapted, when under tension, to normally revolve said member in said direction. 70
4. In a magazine gun, the combination with a gun stock having a shell receiving tube discharging into the gun breech, of a support on said stock having a shell receiving conduit discharging into said tube, a cover member revolute on said support and covering one side of said conduit, a follower extending into and adapted for travel in said conduit against the rear shell therein and engaged 75 by said member and adapted, when said member is revolved in one direction, to forwardly feed the shells, and a spiral spring connecting said support and said member and adapted, to normally revolve said member in said direction, and placed under tension when said member is revolved in the reverse direction. 80
5. In a magazine gun, a gun stock having a shell receiving tube discharging into the breech and having a lateral shell receiving opening adapted for communication with the discharge end of an auxiliary magazine, and a shell feeding device removably fitted in said tube and closing said opening, said stock having means adapted for the attaching thereto 85 releasably said auxiliary magazine, said stock having outside said tube a receptacle adapted for holding therein said device, when the latter is removed from said tube. 90
6. In a magazine gun, a gun stock having in its under side a notch and having a shell receiving tube discharging into the breech and provided with a lateral opening communicating with said notch, a support fitted in said notch and having means releasably 95 attaching it to said stock and provided with a shell receiving conduit having a nozzle removably fitted in said tube through said opening and discharging toward the gun breech a member revolute on said support, 100 a follower extending into and adapted for travel in said conduit against the rear shell therein, and adapted, when said member is revolved in one direction, to be forced by said member forwardly in said conduit, and 105 means for normally revolving said member in said direction. 110
7. An auxiliary magazine having means for attachment to a gun stock and provided with a spiral shell receiving conduit having a discharge nozzle, said magazine having a 115
- revolute cover member covering one side of said conduit, a spring and a follower actuated by said spring and adapted for travel in said conduit behind and against the rear shell in said conduit, for feeding shells in 120 said conduit through said nozzle. 125
8. In an auxiliary gun magazine, a support having means adapted for attaching it to a gun stock and provided with a spiral shell receiving conduit having a discharge nozzle adapted for insertion into a shell receiving tube of a gun, a cover member revolute on said support and covering one side of said conduit, a follower extending into and adapted for travel in said conduit at the rear of and against the rear shell therein and engaged and moved by said member along said conduit, and adapted, when said member is revolved in one direction, to forwardly feed said shells, and a spring connecting 130 said member and said support arranged to revolve said member in said direction. 135
9. In an auxiliary gun magazine, a support having means adapted for attaching it to a gun stock and provided with a shell receiving conduit having a nozzle adapted to discharge into the gun breech, a cover member revolute on said support and covering one side of said conduit, a follower engaged by said member and extending into and adapted for travel in said conduit at the rear of and against the rear shell therein and engaged and moved by said member along said conduit, and a spiral spring connecting said support and said member and adapted to normally revolve said member in a direction for the forward feeding of said shells in said conduit by said follower, said spring being adapted to be wound when said member is revolved in the reverse direction. 140
10. In an auxiliary gun magazine, a support having means adapted for attaching it to a gun stock and having a spiral shell receiving conduit provided with a nozzle adapted to discharge into the gun breech, 145 a cover member revolute on said support and covering one side of said conduit, a follower pivoted to said member and extending into and adapted for travel in said conduit at the rear of and against the rear shell therein, and a spring arranged when under tension to normally revolve said member in a direction such that the follower will forwardly feed said shells in said conduit. 150
11. In an auxiliary gun magazine, a revolute member, a support having means adapted for attaching it to a gun stock and having a spiral shell receiving conduit encircling the axis of said member and provided with a nozzle adapted to discharge into the gun breech, said member being revolute on said support, a follower movable on said member toward and from the axis of the latter and extending into and adapted for travel in said conduit at the rear of and against the rear 155

shell therein, for forcing said shells forwardly when said member is revolved in one direction, and a spiral spring connecting said support and said member and arranged to revolve said member in said direction, and arranged to be wound when said member is revolved in the reverse direction.

12. In an auxiliary gun magazine, a support having means adapted for attaching it to a gun stock and provided with a spiral shell receiving conduit having a nozzle adapted to discharge into the gun breech, a cover member revoluble on said support and covering one side of said conduit, said conduit encircling the axis of said member, said member having a slot communicating with said conduit and extending across the coils thereof, a follower pivoted to said member and having an arm extending into and adapted for travel in said slot and in said conduit at the rear of and against the rear shell in said conduit, and movable out of said conduit, and adapted to feed forwardly the shells in said conduit, when the said member is revolved in one direction, and means for normally revolving said member in said direction.

13. In an auxiliary gun magazine, a support member having means adapted for attaching it to a gun stock and having a spiral shell receiving conduit having a nozzle adapted for discharging into the gun breech, a cover member revoluble on said support and covering one side of said conduit and having a slot crossing and communicating with the coils of said conduit, a follower pivoted to said member and having an arm extending into and adapted for travel in said slot and said conduit at the rear of and against the rear shell in said conduit, and adapted, when said member is revolved in one direction to feed forwardly said shells and adapted for withdrawal from said conduit, and a spiral spring connecting said support and said member and arranged to normally revolve the latter in said direction.

14. In an auxiliary gun magazine, a support having means adapted for attaching it to a gun stock and having a spiral shell receiving conduit having a discharge nozzle adapted for insertion into and to discharge toward the gun breech in a shell receiving tube in said stock, a member revoluble on said support and having a slot crossing and communicating with the coils of said conduit, a follower comprising a plate pivoted to said member, a pin extending into said slot and said conduit and adapted for travel at the rear of and against the rear shell in said conduit and adapted to feed said shells forwardly when said member is revolved in one direction, said pin being movable on said plate out of said conduit and having releasable means for being held out of said conduit, and

a spring for normally forcing said pin into said conduit, and means for normally revolving said member in said direction.

In testimony whereof we have signed our names to this specification.

NORMAN E. McCORMICK.
